UNITED STATES PATENT OFFICE

91,051

DESIGN FOR A BANDEAU

Siegfried Behr, New York, N. Y.

Application August 1, 1933. Serial No. 48,904

Term of patent 3½ years

To all whom it may concern:

Be it known that I, SIEGFRIED BEHR, a citizen of the United States, residing at 302 Fifth Ave., New York, in the county and State of New York, have invented a new, original, and ornamental Design for a Bandeau, of which the following is a specification, reference being had to the accompanying drawing, forming a part thereof in which:

Fig. 1 is a front elevation of the bandeau.

Fig. 2 is a plan of the bandeau seen from the bottom of Fig. 1.

Fig. 3 is a side elevation of the bandeau seen from the right of Fig. 1.

The bandeau is featured by a curved flat band from which a feather-like ornament extends vertically upward.

I claim:

The ornamental design for a bandeau as shown and described.

SIEGFRIED BEHR.
